UNITED STATES PATENT OFFICE.

JOHN A. HELLSTROM, OF WHEELING, WEST VIRGINIA.

MACHINE FOR SEPARATING METAL SHEETS.

Application filed February 1, 1922. Serial No. 533,441.

To all whom it may concern:

Be it known that I, JOHN A. HELLSTROM, a subject of the King of Sweden, and resident of Wheeling, county of Ohio, 5 and State of West Virginia, have invented certain new and useful Improvements in Machines for Separating Metal Sheets, of which the following is a specification.

This invention relates broadly to apparatus of the class or type commonly termed "sheet openers", and more specifically to mechanism for separating the adhering sheets of metal packs.

The primary object of the invention is to provide mechanism whereby metal sheets which have become bonded in the rolling of the pack have their bonds broken by an operation in which the sheets are bodily stripped one from the other.

20 A further object is to provide a sheet separating mechanism by which the separated sheets are delivered in a flattened condition, ready for piling, as distinguished from the irregular, curled, or otherwise distorted forms common to delivery from prior mechanisms of the general type to which this invention belongs.

With these and other objects in view, the invention resides in the features of construction, arrangement of parts and combinations of elements which will hereinafter be fully described, reference being had to the accompanying drawings, in which—

Figure 1 is a front elevation of a machine 35 constructed in accordance with my invention;

Figure 2 is a section on line 2—2, Fig. 1;

Figure 3 is a top plan view of said machine; and—

40 Figure 4 is an enlarged section of the rolls and spreader bar.

Referring to said drawings, 1 indicates roll housings in which are arranged suitable bearings 2 and 3 carrying rolls 4 and 5, respectively, the upper bearings 2 being carried by vertically movable rods 6 sustained by coil springs 7 which, through the intermediate parts referred to, normally serve to yieldingly support said upper roll 4 in an 50 elevated position. Screws 8 mounted in the upper parts of the housings have their lower ends seated upon the upper bearings and are adapted to be adjusted downward against the tension of the springs 7 for lowering the 55 roll 4 with respect to the roll 5. It will be noted that a more or less conventional con-

struction and arrangement is involved in the foregoing.

Located in front of the rolls is a transverse spreader bar 9 having its ends rigidly supported on the roll housings. As herein shown, said bar is ovoidoconical in form in cross section and is positioned so that the blunt ridge-like edge 9^a thereof is presented toward and in the plane of the pass between 65 the rolls. Further, the position of said bar is such that narrow feed passages or guideways for sheets are provided between the convergently inclined upper and lower sides of said ridge and the upper and lower rolls, 70 respectively.

While the form of spreader bar above described is at present preferred, it is to be understood that bars or rods of other forms as, for instance, a rod of true cylindrical 75 form, may be substituted therefor.

In practice, the operator spreads apart the ends of the sheets 10 to be separated and, with the sheets resting, or partially resting, upon the feed table 11, he introduces the said 80 edges of the upper and lower sheets through the upper and lower guideways, respectively, to a position where they are together seized by the rolls, which latter then act to draw said sheets inward, as shown in Fig. 4, and 85 to deliver the same to a table 12, preferably of roller form, by which they are advanced to an out-of-the-way position. As is obvious, the rolls exert a powerful traction for drawing the sheets over opposite sides of the 90 spreader bar, whereby said sheets are forcibly stripped one from the other.

Due to the substantial correspondence in the diameters of the rolls 4 and 5, the sheets are delivered flat as distinguished from the 95 objectionable curled form assumed by sheets passed between rolls of notably unequal diameters.

To enable the operator to effect prompt release of the sheets 10, as when the same 100 have not been entered properly between the rolls, means is provided whereby the upper roll 4 may be instantly allowed to move upward, or away from the roll 5, under the force exerted by the springs 7. Said means comprises an arm 13 rigidly carried by each of the adjusting screws 8 and having handle portions 14 which extend to suitable points in which one or the other thereof will always be within convenient reach of the operator. 110 A transverse tie-rod or bar 15 connects said arms so that lateral swinging movement

given to either arm for producing rotary movement of one screw is imparted in equal measure through the other arm to the other screw. It will be understood that the 5 thread-pitch of the screw is such that a small fractional part of a rearward revolution suffices to allow the roll 4 to be elevated out of frictional drawing relation to underlying sheets. Thus, a slight blow of the hand 10 of the operator against either handle 14 in a direction for reversing the screws will suffice to effect release of sheets gripped by the rolls.

What is claimed is—

- 15 1. A sheet separating apparatus comprising upper and lower rolls arranged in co-operative sheet-advancing relation, and a spreader bar located in front of the pass between said rolls and spaced from the latter to provide upper and lower guideways leading to said pass.
- 20 2. A sheet separating apparatus comprising upper and lower rolls arranged in co-operative sheet-advancing relation, and a spreader bar located in front of the pass between said rolls and spaced from the latter to provide upper and lower guideways leading to said pass, said bar having a tapered ridge presented toward and in the plane 30 of said pass.
- 25 3. A sheet separating apparatus comprising upper and lower rolls arranged in co-operative sheet-advancing relation, the upper roll being shiftable vertically with respect to the lower roll, and a spreader bar located in front of and at a spaced distance from said rolls whereby are provided two 35

convergently inclined guideways leading to the pass between said rolls.

4. A sheet separating apparatus comprising upper and lower rolls arranged in co-operative sheet-advancing relation, the upper roll being shiftable vertically with respect to the lower roll, and a spreader bar located in front of the pass between said 40 rolls, said bar being substantially ovoido-conical in cross section and presenting its ridge-like edge toward said pass, said bar being spaced relative to said rolls to provide two convergently inclined guideways leading to said pass.

5. A sheet separating apparatus comprising housings, upper and lower bearings in said housings, rolls journaled in said bearings and adapted to cooperate for advancing sheets introduced therebetween, the upper bearing being shiftable vertically for moving the upper roll into and out of co-operative relation to the lower roll, a feed table located in front of said rolls, and a 55 transverse spreader bar supported by said housings over the inner end of said table and positioned to provide intermediate its upper and under sides and the upper and lower rolls, respectively, convergently inclined passages through which sheets are guided to the pass between said rolls.

In testimony whereof, I affix my signature in presence of two subscribing witnesses.

JOHN A. HELLSTROM.
